HERMAN REINECKE, OF NEW YORK, N. Y.

Letters Patent No. 65,944, dated June 18, 1867.
Antedated June 10, 1867.

IMPROVEMENT IN ESCAPEMENTS FOR TIME-PIECES.

The Schedule referred to in these Letters Patent and making part of the same.

TO ALL WHOM IT MAY CONCERN:

Be it known that I, HERMAN REINECKE, of the city, county, and State of New York, have invented a new and improved Escapement for Time-Pieces; and I do hereby declare that the following is a full, clear, and exact description thereof, which will enable others skilled in the art to make and use the same, reference being had to the accompanying drawings, forming part of this specification, in which—

Figure 1 represents a sectional front elevation of this invention.

Figure 2 is a side elevation of the same.

Similar letters of reference indicate like parts.

This invention relates to a mechanism which combines the advantages of the detached escapement with the lever escapement, the balance being so arranged that it receives an impulse from the escape-wheel, while it swings in one direction only, being perfectly free from the power of the main-spring during the other half of its motion, and the impulse produced by the escape-wheel is transmitted to the balance by means of a lever.

A represents the escape-wheel, and B the balance, which is mounted on the arbor or staff α . The escape-wheel has a tendency to revolve, under the action of the main-spring, in the direction of the arrow marked thereon in fig. 1, and its teeth act on the pallets $p p'$, which project from a bar mounted on the arbor b , the pallet p being so shaped that the same fits between two succeeding teeth of the escape-wheel, and that when the arbor b is turned in the direction of the arrow marked near it in fig. 1, so as to raise the pallet p , the joint of the tooth of the escape-wheel glides down over the inclined face of said pallet, and as the tooth leaves the pallet p , the next preceding tooth strikes the pallet p , and causes the pallet to drop again between the teeth to the position in which it is shown in fig. 1. The oscillating motion of the arbor b is produced by the action of a pin, c , which projects from the hub of the balance, and which acts on a lever, C , that is mounted on the arbor b . From the end of this lever project two pins, $d e$, and a lifting-spring, f , bears against the pin e . The pin d acts on a pin, g , projecting from the hub of the balance, and serves to impart to said balance the required impulses. If the balance swings in the direction of the arrow, marked on it in fig. 1, the pin c passes the lifting-spring f without producing any motion of the lever C , and the pallets are not disengaged from the escape-wheel; but if the balance returns in the direction opposite the arrow marked on it, the pin c , on coming in contact with the lifting-spring, causes the lever C and arbor b to turn in the direction of the arrow marked near it in fig. 1, and the pallet p rises, allowing the tooth of the escape-wheel to slide down on its inclined edge. As soon as the tooth strikes the inclined edge of the pallet, the pin d is thrown in contact with the pin g , in the hub of the balance, and an impulse is given to said balance sufficient to keep up its motion. When the pin c has passed the lifting-spring, the lever C returns to its original position by the action of the escape-wheel on the pallet p' , and the balance, in swinging in the direction of the arrow marked on it in fig. 1, is relieved entirely of the force of the main-spring, and it has to overcome no obstruction besides the friction, the resistance of the air, and that of the lifting-spring. By this arrangement an escapement is obtained in which the impulses imparted to the balance are as near as possible uniform, and furthermore, during a large part of its motion, the balance is entirely relieved of the power of the main-spring, and its oscillations become isochronic.

My escapement is applicable, with equal advantage, to a horizontal or to a vertical balance, and it can be used for clock movements as well as for watches.

What I claim as new, and desire to secure by Letters Patent, is—

The pallets $p p'$, mounted on the oscillating arbor b , in combination with the lever C , lifting-spring f , pins $d e g c$, and balance B , all constructed and operating substantially as and for the purpose described.

HERMAN REINECKE.
